BILFOLD

Irving Schwartz, Newton, Mass., assignor to
Knight Leather Products, Inc., Boston, Mass.,
a corporation of Massachusetts

Application August 5, 1937, Serial No. 157,535

1 Claim. (Cl. 150—39)

This invention relates to bill folds and the like articles, which are usually carried on the person.

Bill folds of conventional design and construction are usually provided with a plurality of pockets arranged in juxtaposed relation and adapted to receive various personal effects, the top pocket usually being provided with a transparent parent wall so as to expose at least part of its contents, such as the face of an identification card, an operator's license, or the like certificate. The routine of the average individual usually requires him to carry on his person several such papers, cards or certificates, which fill up the various pockets and cause the bill fold to assume a bulky appearance. As the use of such papers or certificates as railroad passes, operator's licenses, etc., is generally confined to a mere visual inspection, it is highly desirable that provision be made not only to receive such papers so that they may be adequately protected from injury due to handling, but also to support them in a manner permitting ready inspection.

The principal object of the present invention is to provide a bill fold which satisfies the aforementioned desirable features without unduly increasing the bulk of the bill fold or its cost of manufacture, and without impairing the accessibility to its pockets or its use for any of the various purposes to which such articles are susceptible.

Further objects will be apparent from a consideration of the following description and accompanying drawing, wherein:

Fig. 1 is a top plan view of a bill fold constructed in accordance with the present invention;

Fig. 2 is an enlarged section on the line 2—2 of Fig. 1;

Fig. 3 is an enlarged section on the line 3—3 of Fig. 1; and

Fig. 4 is a fragmentary perspective of the front end of the bill fold, showing the outer pocket swung open.

The embodiment chosen for illustration comprises a bill fold having juxtaposed pieces of leather or the like sheet material 1 and 2 (Figs. 2 and 3) secured together at their edges in any suitable manner, as by a line of stitching 4, to provide a main pocket having a set of interlocking fasteners 5 operated by a slider 6 which carries a pull 7, as shown in Fig. 1. The wall 2 forms the rear wall for a pair of outer pockets 10 and 11 defined by outer wall members which may consist of pieces of leather or the like sheet material 14 and 15 stitched or otherwise secured

at or adjacent to the marginal portions of the two halves of the wall 2 with their grain or finished surface facing outwardly and their inner ends spaced from each other so as to provide access to each pocket.

The wall 14 is provided with a U-shaped cut 16 which is spaced from and extends about its sides and one end, thus forming a flap 18 hinged at 19 to the wall 14. A transparent piece of sheet material, such as a sheet of celluloid 20 is stitched or otherwise secured to the under surface of the margins of the wall 14 and provides a window for the pocket 10. As here shown, the same row of stitching 4 which secures the walls 1 and 2 together, may be used to secure the sheet 20 and the wall 14 in position, although it is to be understood that the particular manner of securing the different parts may be varied in accordance with the design and other considerations.

A sheet of celluloid or the like transparent material 22, having a marginal binding strip 23 along its side edges, is stitched to the margins at the sides and free end of the flap 18 by a row of stitches 24, thus providing a pocket 25 hinged to the body of the bill fold so as to be swung from a closed position, shown in Figs. 1 and 2, to an open position, as illustrated in Fig. 4. As the transparent sheet 20 is secured to the under surface of the wall 14, the marginal portions surrounding the cutout 16 define a shallow recess adapted to receive the inner wall 22 of the pocket 25, as shown in Fig. 2, and accordingly the thickness or bulk of the bill fold is not materially increased by the pocket 25.

Both pockets 10 and 25 are adapted to receive such cards or papers as an operator's license, a railroad pass, an identification card, or the like, which, in the case of the pocket 10, may be inserted through the opening adjacent to the center of the bill fold, and in the case of the pocket 25, may be inserted through the opening at the free end of the flap 18. If desired, such opening may be provided adjacent to the hinge 19, in which case the line of stitching 24 may extend about the margins at the free end of the flap 18. In either case the contents of the pocket are effectively retained when the flap is closed, as shown in Figs. 1 and 2.

Since both the transparent sheets or windows 20 and 22 are covered when the flap 18 is in closed position, these parts are protected so that there is no danger of them becoming scarred, injured or soiled, and the nature and contents of a card or paper inserted in either pocket may

be readily ascertained at a glance simply by swinging the flap 18 outwardly, as illustrated in Fig. 4.

- 5 The opposite half of the bill fold may be provided with a pocket having a construction similar to that above described, or, if desired, it may be provided with a "change pocket" 30 comprising a flap 31 cut out of the wall 15 and secured to a suitable strip or the like (not shown) 10 to provide rear and/or side walls of the pocket. The opening to the pocket 30 may be provided with a closure flap 32 which carries the socket member 33 of a snap fastener, the cooperating stud member being carried by the flap 31.
- 15 While I have shown and described one desirable embodiment of the invention it is to be understood that this disclosure is for the purpose of illustration, and that various changes in shape,

proportion and arrangement of parts, as well as the substitution of equivalent elements for those herein shown and described, may be made without departing from the spirit and scope of the invention as set forth in the appended claim. 5

I claim:

A bill fold or the like article which comprises juxtaposed pieces of sheet material secured along adjacent edges to provide a pocket, one of said pieces of sheet material having a partially cut-out area defining a hinged flap, a sheet of transparent material secured about the margins surrounding said cut-out area to provide a window for said pocket, said flap having a piece of transparent sheet material secured to its marginal portions to provide a second pocket pivotally connected to the first pocket. 10 15
